MACHINE FOR MAKING COLLAPSIBLE AND EXPANSIBLE TUBES

Samuel D. Polsen and Sven Herbert Nelson, Bridgeport, Conn., assignors of one-fourth to Blanche H. Polsen, one-fourth to Mildred P. Nelson, one-fourth to said Sven Herbert Nelson, and one-fourth to Norman Hubbell Nelson, all of Bridgeport, Conn.

Application October 18, 1945, Serial No. 622,970

15 Claims. (Cl. 93—80)

1

This invention relates to new and useful improvements in creasing or folding mechanisms and has particular relation to a means for making collapsible or bellows-like tubes.

The objects and advantages of the invention will become apparent from a consideration of the following detailed description taken in connection with the accompanying drawings wherein satisfactory embodiments of the invention are shown. However, it is to be understood that the invention is not limited to the details disclosed but includes all such variations and modifications as fall within the spirit of the invention and the scope of the appended claims.

In the drawings:

Fig. 1 is a top plan view of a mechanism made according to the invention;

Fig. 2 is a side elevational view thereof;

Fig. 3 is a vertical transverse sectional view taken as along the line 3—3 of Fig. 1;

Fig. 4 is an end elevational view looking from the right in Fig. 2 but with the entrance device removed;

Fig. 5 is an end elevational view of the entrance device;

Fig. 6 is a longitudinal sectional view, on a somewhat larger scale, through a short length of tube made on the present mechanism;

Fig. 7 is a plan view of a modified construction;

Fig. 8 is a longitudinal sectional view through the device of Fig. 7;

Fig. 9 is a transverse sectional view as on the plane of the line 9—9 of Fig. 8; and

Fig. 10 is a rear elevational view of a portion of the device with the drive pulley removed.

The present device or machine comprises means for converting a strip of paper or other material into an expandable and collapsible bellows-like tube. A short section of such a tube is illustrated in Fig. 6 and is generally designated 40. The means of the invention is of simple and inexpensive construction and is adapted for continuous operation, the idea being that a tube would be formed of indefinite length, depending on the length of the strip that is being fed to the means, and that the required lengths for any particular purpose would be cut from the formed tube. Herein, we have not disclosed any means for cutting the tube to the desired length but it will be understood that in practise as the required length of tube is formed, it may be cut off and collapsed so as to occupy but a small space.

Two different forms or means for the purpose suggested are herein disclosed and while the two forms have much in common, the means shown

2

in Figs. 1 through 5 will first be described. Such means, generally designated 11, comprise a casting including a back wall 12 of elongated rectangular shape and from the corner portions of one side of which extend four post-like projections 13, 14, 15 and 16. Additionally, at the inner end of the wall 12 the mentioned casting includes a projecting plate-like extension 17.

A pair of screws 18 or any other suitable means serves to secure an entrance device 19 onto the forward side of the extension 17. This entrance device comprises a combined preliminary forming means and guide for the paper strip being fed to the present means and in the drawing the strip is shown in dotted lines and designated 20. Entrance device 19 comprises a body portion 21 provided in its upper side with a cavity 22 opening through such sides. This cavity, as suggested in Fig. 2, is quite shallow at the entrance end 23 of the device and gradually increases in depth towards the discharge end 24 at which end the cavity is more or less in the form of the letter W as shown in Fig. 5.

Disposed on the upper side of body 21 is a plate 25 including a pair of depending portions 26 shaped to enter the cavity 22. Screws or similar means 27 secure plate 25 to body 21 and the relation of the parts is such that the depending portions 26 do not engage the walls of the cavity 22 so that a preliminary forming slot or passage 28 is provided through the device 19 in the form of the letter W at the discharge end of said device 19 and the paper strip or the like 20 being fed through such passage is forced to take the same shape as that of the passage.

A plate 29 is secured on the outer ends of the posts 13 through 16 as by screws 30 and dowel pins 30a. This plate, together with the rear wall 12 of the main casting, provides means for rotatably mounting the respective end portions of a series of shafts as will appear and in addition the plate forms a measure of protection or guard means to partially enclose devices mounted on said shafts.

In its rear side wall 12 is provided with an annular cavity 31 providing a bearing fitting an internal ring gear 32 formed integral with and extending inwardly from a pulley 33 which may be provided with a groove 34 to receive a V-shaped driving belt. A ring 35, held in place by screws 36, overlaps an annular flange 37 on the pulley 33 and serves to mount the pulley and the internal ring gear on the wall 12 for turning movement. The ring gear 32 meshes with and serves to drive a series of pinions.

Pinions 38, 39, 40, 41 and 42 are mounted respectively on shafts 43, 44, 45, 46 and 47, journaled in and extending between the wall 12 and the plate 29. It is noted that the gears 38 through 42 are located at the outer side of the wall 12 and within a skirt-like portion of the pulley 33, which skirt-like portion comprises the internal ring gear 32 with which the pinions mesh.

In its forward or inner face wall 12 is provided with a recess or cavity 48 and within such cavity 10 a pinion 49 is made fast to the shaft 44 and such pinion meshes with a relatively large gear 50 fixed on a shaft 51, also journaled in wall 12 and plate 29, and which large gear in turn meshes with a small gear or pinion 52. On the shaft 51, between wall 12 and plate 29, is a glue or adhesive applying roller 88 operating partly in an adhesive receptacle 89 and adapted to apply adhesive from said receptacle to the paper strip as will later appear. Alternatively the roller 88 may apply moisture or heat to a pre-glued edge portion of the strip to render such portions adhesive. Pinion 52 meshes with pinion 53, in turn meshing with a pinion 54 and such pinions 52, 53, and 54, are mounted on shafts 55, 56 and 57, each journaled in the wall 12 and plate 29.

From the foregoing, it will be clear that as the pulley 33 is driven, the gear 39 will be rotated and will serve to drive shaft 44 and thus gear 49. The latter meshing with gear 50 serves to drive the same and thus the roller 88 and in addition gear 50 drives gear 52 resulting in the driving of gears 53 and 54, the latter being rotated from the former.

Shafts 56 and 57 are located respectively below and above the outlet or discharge end of the preliminary forming slot 28. Mounted fast on the shaft 56 is a roller 58 and mounted fast on the shaft 57 is a roller 59. Roller 58 is bevelled at its outer end and intermediate its ends is provided with a pair of annular grooves, each V-shaped in transverse section. Roller 59 is bevelled on its outer ends and intermediate such ends is provided with a single annular groove, also V-shaped in transverse section. Thus, the construction of roller 58 is substantially that of three bevelled discs while the construction of roller 59 is that of two bevelled discs.

The relationship of the centers of the shafts 56 and 57 to the diameter of the rollers 58 and 59 is such that the bevelled edges or the disc-like portions of roller 59 interfit with or overlap with those of roller 58 whereby the pair of rollers define between them a slot 60 in the form of the letter W and corresponding with the slot 28 above mentioned. Rollers 58 and 59 are preferably of some resilient or yielding material and are so located that they receive between them in the mentioned W-shaped slot 60 the preliminarily formed paper strip discharged from the entrance device 19. Since when the pulley 33 is being driven the rollers 58 and 59 are also being driven they serve to draw the paper strip through the entrance device 19. From the rollers 58 and 59 the paper strip now somewhat in the form of the letter N is fed across the receptacle 89 and the roller 88 operating in said receptacle applies adhesive moisture or heat to an edge portion of the strip.

The shafts 43, 44, 45, 46 and 47 have rollers 61, 62, 63, 64 and 65 fast thereon and such rollers are grouped in equally spaced relation about a stationary screw 66 whose outside diameter corresponds with the inside diameter of the collapsible and expandable tube to be formed. Rollers 75 through 5 the rollers 58 and 59 serve to push the

61 through 65 are of the general construction of the rollers 58 and 59 above described and their outer edge portions interfit with the threads of the screw 66. These rollers, 61 through 65, are also of rubber or other compressible or yieldable material and their relation to the screw 66 is such that the paper being formed when received between such rollers and screw is pressed tight against the latter by the former.

Screw 66 is shown as being provided with a threaded stud 67 passing through the wall 12 of the main casting in concentric relation with the various shafts 43 through 47. A nut 68 is threaded to the stud 67 and thereby serves to hold the screw 66 drawn against the inner side of the wall 12 and against movement relative to said wall. If desired, pulley 33 may have a flange 69 riding on the intermediate portion of the nut 68 to assist in the steadyng of the motion of the pulley. Screw 66 enters partly into an opening 70 in the plate 29 and which opening is concentric with a screw and of slightly greater diameter than the latter. If desired, this screw may terminate flush with the outer side of plate 29.

25 As the paper strip passes between the rollers 58 and 59 it is creased at two places so that it is somewhat in the shape of the letter N including (see Fig. 6) three arms or portions 71, 72 and 73 and in this condition the roller 88 applies 30 adhesive moisture or heat to the inner side of the lower edge portion of the arm 73. As the strip is moved beyond the adhesive applying roller it enters between the upper side of the screw 66 and the roller 61. The latter presses the already 35 partly formed strip into the threads of the screw and feeds the strip over the screw to the roller 65 and the latter continues to press the strip into the threads of the screw and feeds the strip to the roller 64 which functions to pass the strip 40 to the roller 63 while the latter feeds the strip to the roller 62.

45 As the strip is being fed by these rollers it is forced along the screw 66 because of the pitch of the threads of the latter and as the strip makes one turn about the screw and begins its second turn the glued inner surface of the arm 73 of one portion of the strip is brought over the outer surface of the arm 71 of the next adjacent turn of the strip about the screw and therefore 50 after each turn of the strip is similarly treated and the rollers press the parts together at the adhesively connected joint.

55 The described operation continues and as it continues the strip advances along the screw 66 and is fed out over the end of the screw through the opening 70 as at 74. Just as the strip leaves the screw, a cutter (not shown) may be mounted to sever the formed tube into the desired lengths. These lengths may be readily collapsed into very 60 short tubes since the various rollers have sharply creased the paper and any section of the tube may be collapsed and expanded somewhat in the manner of the collapse and expansion of a bellows or an accordion. Once the strip has been 65 started through the machine there is no reason to stop operations unless or until the end of the strip is reached and thus the means of the invention is adapted by continuous operation for the production of a collapsible and expandable 70 bellows-like tube of paper or other material.

Referring now to the modification of Figs. 7, 8, 9 and 10, the means there shown is somewhat similar to that already described and differs therefrom essentially in that while in Figs. 1

paper strip toward the screw 66 and the associated rollers and that such associated rollers serve to push the paper strip about and along the screw in the modification the arrangement is such that the rollers associated with the screw serve to pull the paper along and about the screw.

In the modification the means of the invention is generally designated 75 and where the parts are the same as previously described they are identified by the same reference characters.

In the modification a screw 76 is associated with rollers 61, 62, 63, 64 and 65 and such screw is of the desired diameter and serves the purpose of the screw 66 above described. A pair of small screws or the like 77 passing through the back wall 12 serves to rigidly mount the screw 76 and the latter is disposed with its free end opposite an opening 78 corresponding with it for the purpose of the opening 70 described in connection with Figs. 1 through 5.

Screw 76 towards its inner end is cut out or cut away to provide a pair of recesses 79 and 80 receiving, respectively, short rollers 81 and 82 fast on shafts 83 and 84 respectively. At their respective ends such shafts are journaled in the wall 12 and the body of screw 76 (see Fig. 9) and such shafts are parallel with the shafts 43 through 47. At the outer side of wall 12 gears 85 and 86 are fast to the shafts 83 and 84 respectively and such gears mesh with the gears 38 and 40 respectively.

With this construction it will be seen that as the rollers grouped about the screw 76 are rotated (through pulley 33 and internal ring gear 32) the rollers 81 and 82 will also be rotated and will rotate in the direction opposite to the direction of rotation of the rollers 61 and 63 respectively. Rollers 81 and 82 are of steel or other unyielding material and have close interlocking fits with the rollers 61 and 63 respectively. Thus, as the paper strip comes between the rollers 61 and 81 the strip is sharply creased and is pulled along over the adhesive moisture or heat applying roller 88.

When the strip is moved about the screw 76 it is similarly treated between the rollers 63 and 82. Since these pairs of rollers characterize the modified construction or relatively close relation, it will be understood that the paper is sharply creased between them and further because of their direction of movement the paper is pulled along through the device by the characterizing pairs of rollers. As the strip is carried about the screw 76 it is fed along the same depending on the thread pitch in the latter and as the tube is formed it passes out through the opening 78 over the free end of the screw. The tube may be cut to lengths and the lengths collapsed as suggested in connection with Figs. 1 through 5. Since in the modification the strip is pulled along about the screw 76 it is noted that the feeding rollers 58 and 59 of Figs. 1 through 5 have been omitted from the modification.

Having thus set forth the nature of our invention, what we claim is:

1. In a mechanism for forming a collapsible and expansible bellows-like tube from a strip of paper or the like, a body and an entrance device having at least three angularly related channels communicating at their longitudinal edges and of gradually increasing depth toward said body, feeding rollers within said body and receiving a strip of material passing inwardly through said entrance, one of said rollers com-

prising a body having at least two V-shaped grooves and this other roller comprising a body having a sectionally V-shaped edge entering partly into each V-groove of the first roller whereby said rollers grip the strip and draw it through said entrance device, a relatively large diameter screw inwardly of and parallel with said feed rollers, other rollers including V-shaped portions entering into the threads of said screw at spaced points about the same, a pulley, a driving connection between said pulley and each of the last mentioned rollers whereby to have the latter press the strip into the threads of the screw and feed the strip along the threads of the screw, and means driving the feed rollers from said pulley.

2. In a mechanism for forming a collapsible and expansible bellows-like tube from a strip of paper or the like, a screw of an outside diameter corresponding with an inside diameter of the tube desired, means providing an entrance slot having angularly related walls for preliminarily forming and creasing a strip, rotatable means associated with said screw for pressing said preliminarily formed strip about said screw and into the threads thereof to further crease said strip, and said screw stationary and said means pressing the strip against the threads of the screw and having driving engagement with the strip whereby to continuously feed the strip along the threads of the screw.

3. In a mechanism for forming a collapsible and expansible bellows-like tube from a strip of paper or the like, a screw of an outside diameter corresponding with an inside diameter of the tube desired, means providing an entrance slot having angularly related walls for preliminarily forming and creasing a strip, rotatable means associated with said screw for pressing said preliminarily formed strip about said screw and into the threads thereof with portions of each turn of the strip about the screw overlapping a portion of the preceding turn of the strip about the screw, means for rendering one of said strip portions adhesive as the strip approaches said screw, and said screw stationary and said means pressing the strip against the threads of the screw and having driving engagement with the strip whereby to continuously feed the strip along the threads of the screw.

4. In a mechanism for forming a collapsible and expansible bellows-like tube from a strip of paper or the like, a stationary screw of an outside diameter corresponding with an inside diameter of the tube desired, means providing an entrance slot having angularly related walls for preliminarily forming and creasing a strip, a pair of oppositely turning rollers at the discharge end of said slot for drawing the strip through the slot and feeding it toward said screw, and means associated with said screw for pressing said preliminarily formed strip about said screw and into and along the threads thereof to further crease said strip.

5. In a mechanism for forming a collapsible and expansible bellows-like tube from a strip of paper or the like, a stationary screw of an outside diameter corresponding with an inside diameter of the tube desired, means providing an entrance slot having angularly related walls for preliminarily forming and creasing a strip, a pair of oppositely turning rollers at the discharge end of said slot for drawing the strip through the slot and feeding it toward said screw, means associated with said screw for pressing said prelimi-

nearly formed strip about said screw and into and along the threads thereof with portions of each turn of said strip about the screw overlapping a portion of the preceding turn of the strip about the screw, and means at a place between said oppositely turning rollers and said screw for rendering one of said strip portions adhesive.

6. In a mechanism for forming a collapsible and expansible bellows-like tube from a strip of paper or the like, a stationary screw of an outside diameter corresponding with an inside diameter of the tube desired, means providing an entrance slot having angularly related walls for preliminarily forming and creasing a strip, means associated with said screw for pressing said preliminarily formed strip about said screw and into and along the threads thereof, said last means including a pair of rollers of yieldable material spaced about said screw and including portions to enter the threads of the screw, a pair of similar rollers but of unyielding material recessed into said screw, said rollers of yieldable material including portions interfitting with portions of the respective rollers of unyielding material, means whereby the rollers of yieldable material are driven in the same direction to feed the strip about the screw, means whereby the rollers of unyielding material are driven in the same direction but in a direction opposite to that in which the rollers of yielding material are driven, and said rollers of yieldable material pressing tightly against said rollers of unyieldable material whereby as the strip is fed it is sharply creased.

7. In a mechanism for forming a collapsible and expansible bellows-like tube from a strip of paper or the like, a stationary screw of an outside diameter corresponding with an inside diameter of the tube desired, means providing an entrance slot having angularly related walls for preliminarily forming and creasing a strip, means associated with said screw for pressing said preliminarily formed strip about said screw and into and along the threads thereof and means for pulling said strip about the screw and sharply creasing the strip, said last means including pairs of rollers including interfitting portions adapted to press portions of the strip tightly between them, one of said rollers of each of said pairs recessed into said screw, and means for driving the rollers of the respective pairs in opposite directions but the corresponding rollers of all pairs in the same direction.

8. In a mechanism for forming a collapsible and expansible bellows-like tube from a strip of paper or the like, a body and an entrance device having at least three angularly related channels communicating at their longitudinal edges and of gradually increasing depth toward said body, feeding rollers within said body and receiving a strip of material passing inwardly through said entrance, one of said rollers comprising a body having at least two V-shaped grooves and this other roller comprising a body having a sectionally V-shaped edge entering partly into each mentioned V-groove of the first roller whereby said rollers grip the strip and draw it through said entrance device, a relatively large diameter screw inwardly of and parallel with said feed rollers, other rollers including V-shaped portions entering into the threads of said screw at spaced joints about the same, a pulley, and a driving connection between said pulley and each of the last mentioned rollers whereby to have the latter press the strip into the threads of the screw and feed the strip along the threads of the screw.

9. In a mechanism for forming a collapsible and expansible bellows-like tube from a strip of paper or the like, a stationary frame, a screw of an outside diameter corresponding with an inside diameter of the tube desired, means mounting said screw in fixed position and against turning movement in said frame, a series of rotatable shafts mounted against bodily movement in said frame and radially about said screw and in parallel relation therewith, rollers on said shafts and turnable therewith, said rollers of diameters whereby their peripheries enter the threads of said screw, driving means for continuously rotating said shafts in the same direction and thus for continuously rotating said rollers in the same direction whereby the peripheral portions of the latter entering the threads of the screw engage and press said strip against the walls of the threads of the screw and crease said strip and feed it along the screw with edge portions of each turn of the strip about the screw overlapping an edge portion of the preceding turn of the strip about the screw.

10. In a mechanism for forming a collapsible and expansible bellows-like tube from a strip of paper or the like, a stationary frame, a screw of an outside diameter corresponding with an inside diameter of the tube desired, means mounting said screw in fixed position and against turning movement in said frame, a series of rotatable shafts mounted against bodily movement in said frame and radially about said screw and in parallel relation therewith, rollers on said shafts and turnable therewith, said rollers of diameters whereby their peripheries enter the threads of said screw, driving means for continuously rotating said shafts in the same direction and thus for continuously rotating said rollers in the same direction whereby the peripheral portions of the latter entering the threads of the screw engage and press said strip against the walls of the threads of the screw and crease said strip and feed it along the screw with edge portions of each turn of the strip about the screw overlapping an edge portion of the preceding turn of the strip about the screw, and means in said frame in advance of said rollers and screw for rendering one of said strip edge portions adhesive as the strip approaches the screw whereby such overlapping edge portions are adhered as they are pressed together against the threads of the screw.

11. The mechanism as in claim 9 wherein said rollers are of a resilient material.

12. In a mechanism for forming a collapsible and expansible bellows-like tube from a strip of paper or the like, a stationary screw of an outside diameter corresponding with an inside diameter of the tube desired, means associated with said screw for pressing a strip about said screw and into and along the threads thereof, said last means including a pair of rollers of yieldable material spaced about said screw and including portions to enter the threads of the screw, a pair of similar rollers but of unyielding material recessed into said screw, said rollers of yieldable material including portions interfitting with portions of the respective rollers of unyielding material, means whereby the rollers of yieldable material are driven in the same direction to feed the strip about the screw, means whereby the rollers of unyielding material are driven in the same direction but in a direction opposite to that in which the rollers of yielding material are driven, and said rollers of yieldable material pressing tightly against said rollers of unyieldable

material whereby as the strip is fed it is sharply creased.

13. In a mechanism for forming a collapsible and expansible bellows-like tube from a strip of paper or the like, a stationary screw of an outside diameter corresponding with an inside diameter of the tube desired, means associated with said screw for pressing a strip about said screw and into and along the threads thereof and means for pulling said strip about the screw and sharply creasing the strip, said last means including pairs of rollers including interfitting portions adapted to press portions of the strip tightly between them, one of said rollers of each of said pairs recessed into said screw, and means for driving the rollers of the respective pairs in opposite directions but the corresponding rollers of all pairs in the same direction.

14. In a continuously operating mechanism for forming a collapsible and expansible bellows-like tube of paper or the like, a stationary frame, a screw of an outside diameter corresponding with an inside diameter of the tube desired, means mounting said screw against turning and against bodily movement in said frame, a plurality of rollers radially about said screw and having their axes in parallel relation with one another and with the axis of said screw, said rollers so located with respect to said screw and of such size that the peripheral portions of the rollers extend into and substantially completely fill the valleys between adjacent threads of the screw to crowd the strip to be formed against the sides of the threads of the screw and sharply crease such strip longitudinally, means mounting said rollers in fixed positions against bodily movement in said frame, and means for rotating each of said rollers continuously in the same direction about its own axis to press the strip into the threads of the screw and longitudinally crease the strip and feed it about and along the screw and over one end of the latter with a longitudinal edge portion of one turn of the strip about the screw overlapping a longitudinal edge portion of the preceding turn of the

ping a longitudinal edge portion of the preceding turn of the strip about the screw.

15. In a continuously operating mechanism for forming a collapsible and expansible bellows-like tube of paper or the like, a stationary frame, a screw of an outside diameter corresponding with an inside diameter of the tube desired, means mounting said screw against bodily movement in said frame, a plurality of rollers radially about said screw and having their axes in parallel relation with one another and with the axis of said screw, said rollers so located with respect to said screw and of such size that the peripheral portions of the rollers extend into and substantially completely fill the valleys between adjacent threads of the screw to crowd the strip to be formed against the sides of the threads of the screw and sharply crease such strip longitudinally, means mounting said rollers in said frame and against bodily movement relative thereto, and means for continuously rotating one of said screw and said plurality of rollers continuously in the same direction about its own axis to press the strip into the threads of the screw and longitudinally crease the strip and feed it about and along the screw and over one end of the latter with a longitudinal edge portion of one turn of the strip about the screw overlapping a longitudinal edge portion of the preceding turn of the

30 strip about the screw.
